J. A. BENEDICT.
LOCK FOR SLIDING DOORS.
APPLICATION FILED MAR. 10, 1909.

926,460.

Patented June 29, 1909.

UNITED STATES PATENT OFFICE.

JAMES A. BENEDICT, OF NEW YORK, N. Y.

LOCK FOR SLIDING DOORS.

No. 926,460.

Specification of Letters Patent.

Patented June 29, 1909.

Application filed March 10, 1909. Serial No. 482,446.

To all whom it may concern:

Be it known that I, JAMES A. BENEDICT, a citizen of the United States, and a resident of the city of New York, borough of Manhattan, 5 in the county and State of New York, have invented a new and Improved Lock for Sliding Doors, of which the following is a full, clear, and exact description.

My invention relates to locks for sliding 10 doors, my more particular purpose being to produce a lock requiring no key and easily manipulated by hand for the purpose of securing the door.

More particularly stated, my invention 15 comprehends a plate mounted upon a movable door and sunken thereinto, the plate being provided with a recess of a general annular form, and a hinge member mounted upon some stationary part adjacent to the 20 doorway and provided with a pivotally mounted bolt for engaging the plate by entering the recess thereof, the arrangement of the parts being such that the swinging plate may be swung back into a normal position of 25 inactivity or may be temporarily secured relatively to the plate in the movable door member.

Reference is to be had to the accompanying drawings forming a part of this specification, 30 in which similar characters of reference indicate corresponding parts in all the figures.

Figure 1 is a sectional perspective showing my improved lock in use upon a sliding door; Fig. 2 is a substantially central horizontal section through the parts shown in Fig. 1; Fig. 3 is a horizontal section similar to Fig. 2, but showing the door as moved back and the swinging bolt as occupying its 35 normal position of inactivity; Fig. 4 is a front view of the metallic plate which is carried by the movable door member; Fig. 5 is an edge view of the same; and Fig. 6 is a plan view of the hinge member complete.

Boards 7, 8 are so arranged and supported 40 as to form a door pocket therebetween, and movably mounted within this door-pocket is a door member 9. Carried by the door member 9 and sunken into the same is a metallic plate 10 provided with a recess 11 having 45 the general form of a wedge, and being bounded by a shoulder 12, as will be understood from Fig. 4. The edge of the plate 10 opposite the shoulder 12 registers flush with the adjacent surface of the door member 9, 50 as may be seen at 13, Fig. 3.

A latch 14 is, by aid of a pivot 15, mounted upon the plate 10 and may be turned by hand. The plate 10 is secured upon the door member 9 by aid of screws 16. Mounted upon a stationary post 17 is a plate 18, 60 this plate being secured to the post by aid of screws 19. Journaled upon the plate 18 is a swinging plate 21 which is provided with a knob 22, this knob being of proper size to easily enter a hole 20 in the plate 18. 65

The operation of my device is as follows: When it is desired that the door member 9 may be moved freely in either direction, the swinging plate 21 is turned into the position indicated in Fig. 3, the knob 22 entering the 70 hole 20. The swinging plate 21 is now completely out of the way so as not to interfere with the free movements of the door member. If, however, it be desired to secure the door 9, the door is moved into suitable position, as indicated in Fig. 2, and the swinging 75 plate 21 is moved angularly outward so that the end of the plate engages the shoulder 12. Any movement of the sliding door 9 toward the right, causes the swinging plate 21 to act 80 like a pawl; that is to say, to bite against the shoulder 12 and effectively prevent any travel of the door member toward the right. The operator next turns the latch 14 into such position that it hangs downwardly from the 85 pivot 15, as indicated in Fig. 1. The swinging plate 21 can not now be moved away from the plate 10 until the operator again turns the latch 14 into its normal position which is indicated in Figs. 4 and 5. 90

Having thus described my invention, I claim as new and desire to secure by Letters Patent:

1. A device of the character described, comprising a door member movable in the 95 general direction of its width, a plate mounted upon said door member and provided with a recess having the general form of a wedge and provided with a shoulder, and a plate journaled upon a stationary member disposed adjacent to the path of travel of said door member and adapted to swing, said plate being provided with a portion for entering said recess and engaging said shoulder. 100

2. A device of the character described, 105 comprising a movable door member, a metallic member sunken thereinto and provided with a shoulder, a stationary member disposed adjacent to said movable door member, a plate secured to said stationary 110

member, and another plate pivoted upon said last-mentioned plate and adapted to engage said shoulder of said metallic member.

- 5 3. The combination of a movable member adapted to travel in a door pocket, a stationary member disposed adjacent to said door pocket, a plate mounted upon said stationary member and provided with an opening, a swinging plate pivotally mounted upon said first-mentioned plate and provided with a knob for entering said opening when said swinging plate is turned for this purpose, and a closure member disposed partially within 10 said door pocket and adapted to travel within the same, said door pocket being provided with a portion having a shoulder for

engaging the outer end of said swinging plate.

4. The combination of a movable door, a 20 stationary member disposed adjacent to said door, a plate pivotally mounted upon said stationary member and adapted to be swung toward and from said door, and a latch mounted upon said door and adapted to engage said plate for the purpose of holding the same in engagement with said door. 25

In testimony whereof I have signed my name to this specification in the presence of two subscribing witnesses.

JAMES A. BENEDET
